UNITED STATES PATENT OFFICE.

SALMON W. PUTNAM, OF FITCHBURG, MASSACHUSETTS.

DESIGN FOR A DRILLING-MACHINE FRAME.

SPECIFICATION forming part of Design No. 14,276, dated September 11, 1883.

Application filed July 19, 1883. Term of patent 14 years.

To all whom it may concern:

Be it known that I, SALMON W. PUTNAM, of Fitchburg, in the county of Worcester, State of Massachusetts, have invented and produced 5 a new and original Design for Drilling-Machine Frames, of which the following is a specification, reference being had to the accompanying drawings, forming part thereof.

Figure 1 is a side elevation of my newly-designed drill, and Fig. 2 is an elevation of the opposite side, these two views fully illustrating my design.

My design consists of the goose-neck column, with its rounded vertical end, and having an

upper and lower annular projection, the central arm, A, and the forked and ribbed bracket B integral therewith on the opposite side of the column, the whole surmounting a base or platform, this latter forming, however, no part of my design. 15 20

I claim—

The design for a drilling-machine frame, as herein shown and described.

SALMON W. PUTNAM.
